DYEING BOOSTER

Jack Lewis Green, Duncan, S. C.

Application December 26, 1941, Serial No. 424,483

3 Claims. (Cl. 68—175)

This invention relates to a dyeing method and booster for dyeing fabrics of the type wherein the fabric is continuously passed through a dyeing liquor.

An object of the invention is to devise a dyeing method and booster for greatly increasing the yardage capacity for a given size of booster box; to provide ample time for the proper reduction and development of the most concentrated vat mixes when padded in the pigment or unreduced form; and to provide a dyeing method and apparatus which involves considerable savings in cost of operation over the present jig method of dyeing.

There is a very great need for a dyeing method or process whereby the cloth could be kept in the booster for from four to eight minutes, or for a booster that would hold from 300 to 600 yards of cloth, and which could be run continuously. This booster would necessarily have to be limited in size, as the volume of liquor is a determining factor in the dyeing cost. With a booster capacity of from 300 to 600 yards, color could be applied on the padder in the raw or unreduced state, in which state it is stable at any concentration; and then could be run into the booster box for a long enough time to thoroughly reduce and develop the required shade; thence, it could be washed, oxidized and soaped in the manner that is used at present.

A preferred embodiment of my invention is illustrated in the drawing in which

Figure 1 is a side elevational view of the booster showing the manner in which the fabric is mounted and guided on the series of rollers within the booster vat;

Figure 2 is an end view of Figure 1;

Figure 3 is a plan view of Figure 1; and

Figure 4 is a fragmentary view showing in perspective the manner in which the web is guided out of the center of the booster vat.

Referring to the drawing V indicates a booster vat which may be made of any suitable material such as cast iron, stainless steel, or even of wood. This vat may be of any desired capacity to meet the needs of any particular installation. A series of rolls are mounted in the vat to guide the web of fabric in a spiral arrangement within the vat. These rolls are divided into a number of sets for supporting different sections of the spiral arrangement. For example, rolls A, A₁, A₂ and A₃ are mounted in a rectangular arrangement to support one section of the spiral arrangement; rolls B, B₁, B₂ and B₃ are arranged within the first set of rolls for supporting a second section

of the spiral arrangement, and rolls C, C₁, C₂ and C₃ are arranged within the second set to support a third section of the spiral arrangement. Rolls A, B and C are preferably geared together as shown in the drawing and are driven at a constant speed from a suitable source of power, not shown. In a like manner, rolls A₃, B₃ and C₃ are geared together to be driven at the same speed as rolls A, B and C and preferably from the same source of power. A roll D is mounted in one end of the vat between rolls C₂ and C₃ and parallel with these rolls. A roll E is mounted substantially in the same horizontal plane as D but at an angle of 45° to roll D. Roll F is mounted in a plane just above the plane of roll E and at right angles to roll D, and this roll is positioned at one side of the vat and outside of the spiral arrangement of the web. A similar roll F₁ is mounted vertically above roll F and parallel thereto at the top of the vat, and a roll E₁ is mounted vertically above and parallel with the roll E outside of the vat. The rolls may be made of hard rubber, with a steel shaft or of some non-corrosive alloy, such as stainless steel. All bearings designated as outside bearings are of the roller or ball-type, and all inside bearings can be of any suitable type of material, such as graphite or fibrous composition. The inside rolls are mounted on a stationery frame work, which is not shown, but which may be made in any manner desired. The frame must be placed in such a way as to allow clearance for operation.

Operation

The machine will operate at controlled speed by using rheostats and compensator rolls or by using geared motors to operate at constant tension. Either method will be satisfactory.

The cloth is first run through a two-roll padder, with color box attached, where it is impregnated with pigment or unreduced color (or the color may be reduced if the shade is not too deep). The padder is not shown in the drawing but is located to the left of Figure 1. The path of the web through the vat is represented by the dot-dash line W_a, W_b, W_c, etc., in Figure 1. Coming from the padder, the cloth or web W is run over a roll, designated as "H," and having ball or roller bearings, and then down at W_a and under the free running roll designated A-1; then along W_b and over the roll G-5, and under the free running roll, A-2; then along W_c and over the gear-driven roll, A-3, which is driven at the same speed as the padder is running. It then runs along W_d and over roll G, and over the next driven roll A, and

proceeds back along W_e to roll $A-1$, going on roll $A-1$ inside of the strand of cloth as it comes off of roll H ; the cloth is run in this manner until the total of from fifteen to thirty laps have been run on the "A" series of rolls. The number of laps may be determined by the weight or construction of the cloth, or by the depth of shade desired. From the "A" series of rolls, the cloth comes off at $A-2$ and runs along W_f and over the driven roll $B-3$, and on over the roll $G-1$; then over the driven roll B down under the roll $B-1$, over the roll $G-4$, under the roll $B-2$, and back over roll $B-3$ and inside the strand coming from $A-2$. The "B" series of rolls is then filled in the same manner as the "A" series. Coming off at $B-2$, the cloth is run along W_g and over the driven roll $C-3$, over $G-2$, over the driven roll C , down under $C-1$, over $G-3$, under $C-2$, and back over roll $C-3$ and inside the strand coming from $B-2$. The "C" series of rolls is filled as the others; and then the cloth comes off at $C-3$, and down along W_h and under D , then along W_i , passing under and back over roll E , which is at a forty-five degree angle to the direction of the on-coming cloth, and consequently, turns the cloth over and at right angles to its former direction. It then runs along W_j and passes beneath F , then along W_k up and over $F-1$ and along W_m to $E-1$, which is also at a forty-five degree angle to $F-1$, and running under and back over this roll, the cloth is again turned at right angles as at W_n , and is ready to proceed through the series of boxes for washing, oxidizing and soaping and washing as before mentioned.

As a variation to the method just described, the process could be reversed, and the cloth run in over H , then over and under $E-1$ (which would have to be at a forty-five degree angle to H), and over $F-1$, down to and under F , and over and under E ; over D and down under $C-2$, and back up and over $C-3$. The booster could then be filled from the inside out in the reverse order to the prescribed method, finally coming off of roll $A-2$, and thence through the finishing process as before.

From the foregoing description it will be clear that the web material is arranged on the series of rollers in a spiral arrangement consisting of a plurality of laps or convolutions, the inner end of the spiral being brought laterally out from the center of the spiral in a direction along the axis of the spiral to the side thereof and then upwardly and out of the vat. Different concentric sections of the spiral are supported on different sets of rollers, each set of rollers carrying a plurality of laps or convolutions arranged in contiguous relation, but it will be understood that the apparatus will give satisfactory operation with only one lap or turn on each set of rollers. While only three sets of rollers have been shown, it will be obvious that any desired number of sets may be provided.

The series of rolls designated as "G" are only for the purpose of holding the cloth up and keep it from sagging.

The old dyes are let out to allow re-filling by means of a hole and stopper in the bottom of the vat.

It is the general practise of dyers to have sufficient cloth for filling a machine, and to use this cloth as a leader so that when a lot has been completed, this leader is sewed in at the end, and is left standing in the machine until the next shade is made ready to run or until the machine is operated again.

My improved booster and method of dyeing, by the reason of the fact that it allows an increase of from four to eight times the present possible yardage in a given size booster box, will allow ample time for the proper reduction and development of the most concentrated vat mixes when padded in the pigment form, and will also have the added advantage of giving more color value for those shades that are now run continuously, by reason of the fact that it gives longer time for reduction and development of the shades. There will be a saving in cost of operation by taking the vat work off of the pad and jig method (as hereinbefore explained), and running the same shades constantly, thereby greatly increasing the rate of production and the quality of the work.

I claim:

1. In apparatus for treating web material in a dyeing process, the combination of a vat for holding liquid, a series of rollers for supporting a section of said web in a spiral arrangement within said vat and below the level of said liquid, an inner roller mounted within said spiral arrangement and arranged at an angle to the axis of said spiral for supporting a section of said web extending from the inner end of said spiral and for guiding another section of said web in flat sheet form substantially along the axis of said spiral to one side of said spiral, and another roller positioned within said vat for supporting the outer end of said axial section of said web and for directing another section of said web in flat sheet form in a substantially vertical direction out of said liquid.

2. Dyeing apparatus according to claim 1 wherein said series of rollers are arranged in a number of sets for supporting different concentric sections of said spiral arrangement, and each set of rollers carries a number of turns or laps of said web arranged in contiguous spiral relation.

3. In apparatus for treating web material in a dyeing process, the combination of a vat for holding liquid, a set of web guides mounted within said vat and below the level of said liquid for supporting at least one lap of said web beneath the surface of said liquid, and another set of web guides mounted in said vat for supporting at least one lap of web within but spaced from said first mentioned lap, whereby the laps carried by said two sets of guides are supported in a spiral arrangement below the surface of said liquid, an inner web guide mounted within said spiral and at an angle to the axis thereof for supporting and guiding the inner end of said spiral arrangement in flat sheet form from the center of said spiral laterally to the side thereof, and a web guide mounted outside of said spiral and within said vat for receiving said web from said inner guide and directing said web upwardly and out of said liquid.

JACK L. GREEN.
